United States Patent Office

Des. 199,842
Patented Dec. 22, 1964

199,842

BURIAL VAULT

Thomas J. Neumann and Darrell I. Burrell, both of
P.O. Box 528, Perry, Okla.

Filed June 5, 1963, Ser. No. 75,236

Term of patent 7 years

(Cl. D19—1)

FIG. 1

FIG. 4

FIG. 2

FIG. 3

FIG. 5

We claim:

The ornamental design for a burial vault, substantially as shown and described.
